W. E. BELL.
ELECTRIC SWITCH.
APPLICATION FILED OCT. 18, 1919.

Patented Apr. 27, 1920.

Fig. 1.

UNITED STATES PATENT OFFICE.

WILLIAM E. BELL, OF BOSTON, MASSACHUSETTS.

ELECTRIC SWITCH.

1,338,607.

Specification of Letters Patent. Patented Apr. 27, 1920.

Application filed October 18, 1919. Serial No. 831,725.

To all whom it may concern:

Be it known that I, WILLIAM E. BELL, citizen of the United States, residing at Boston, in the county of Suffolk and State 5 of Massachusetts, have invented new and useful Improvements in Electric Switches, of which the following is a specification.

This invention relates to an automatic switch adapted for use in connection with 10 motor driven motion picture machines, wherein the circuits for the lamp and the motor may be controlled by one piece of apparatus.

It is usual to wire the apparatus and install switches so that the motor and lamp 15 are controlled by separate circuit closing devices. In many localities the underwriter's code calls for a switch for the motor which must be held closed by the operator, 20 against the action of a spring, the switch being normally open. If the operator desires to leave the machine without stopping the motor, he usually ties the handle with a string. This involves danger, on account 25 of the time required to release the switch in the event of the breaking of the film, or other accident.

In the present device the two circuits are controlled by the operation of one switch 30 handle, which can not easily be tampered with in the manner indicated—or in other words, the presence of the operator is required.

In the drawings—

35 Figure 1 is a view in elevation, assuming that the switch is installed with its base in an upright position,

Fig. 2 is a section on the line 2—2 of Fig. 1,

Fig. 3 is an end view,

40 Fig. 4 is a longitudinal section of the handle.

The base 10 may be of any suitable non-conducting material, and mounted thereon are terminals 11, 12, 13 and 14, arranged 45 in pairs as shown. Near these terminals are mounting elements 15, 16, 17, 18, for pivotally supporting the blades 19, 20, 21, 22. The terminal elements are in electrical connection with the blades, and the latter are 50 connected to a yoke 23, of non-conducting material by bolts 24, 25, 26 and 27. The blades coöperate with the contact elements 28, 29, 30, 31, mounted in the base in the required position.

55 Mounted on the yoke 23 is a handle 32, provided with a cap 33 and a ferrule 34, the

handle being threaded at 66 for effecting connection with the yoke. A recess 35 connects with a bore 36, the recess receiving portion 37 of the cap, said portion 37 being 60 recessed as shown at 39. The cap also has a shoulder 38 which abuts the end of the handle.

A plunger 40 is provided with an end portion 41 engaging the body of the cap, and 65 with a flange 42 abutting the end of the recess 39. A spring 45 encircles the plunger 40, being located in the recessed portions of the handle and cap, and the plunger, slid- 70 able with reference to the bore 36, is threaded as at 43 through a yoke 46 and is engaged by a nut 44.

Switch blades 47 and 48 are secured to the yoke 46 (of insulating material), by means of screws 49, 50. The blades may be 75 provided with openings 48^a, and may be provided, respectively with grooves 50^a and 51.

The spring fingers 56, 57, 58, 59 coöperate with the blades, the offset portions 60 engaging the grooves of the blades, and said 80 fingers including mounting elements 61, curved resilient portions 62, and deflected ends 63. In order to maintain the alignment of the vertically movable elements, guide rods 64 and 65 are employed. They 85 are mounted on yoke 46 and pass through yoke 23.

Spring fingers 56, 57, 58, 59 are secured by means of screws 52, 53, 54, 55, and are connected with the motor circuit of the picture machine, and this circuit is closed by pressure on the cap 33, thereby bringing the blades 47, 48 into contact with the fingers last mentioned. The engagement between elements 60 and grooves 50^a and 51 effects 90 good electrical contact, but the constant pressure of the hand on the cap is required in order to maintain the engagement. The lighting circuit or circuits are connected with the remaining terminals on the base, 100 and are controlled by the main switch including yoke 23. If the yoke 46 is tied down, for retaining the motor circuit closed, the yoke 23 may still be swung outwardly, the blades 47, 48 being quickly separated 105 from the ends of the coöperating spring fingers, thereby breaking the circuit of the motor as well as the lighting circuit.

What I claim is—

1. In an electric switch, a base, a plurality 110 of blades pivotally mounted thereon, a yoke connecting the blades, operating means for

- the yoke, contact members coöperating with the blades, a plurality of spring fingers mounted on the base, and adapted for connection with an electric circuit, blades co-
5 operating with the fingers, a yoke connected with the blades last named, and means controlling the yoke last named and causing the blades connected therewith to contact with the spring fingers, said means being
10 mounted on the yoke first named, but having a movement independent thereof.

2. In an electric switch, a base, a plurality of blades pivotally mounted thereon, a yoke

connecting the blades, contact members coöperating with the blades, a plurality of spring 15 fingers mounted on the base and adapted for connection with an electric circuit, blades coöperating with the fingers, a yoke connected with the blades last named, and means for moving the yokes and all of the 20 blades simultaneously to inoperative position, said means permitting movement of one of the yokes independently of the other.

In testimony whereof I affix my signature.

WILLIAM E. BELL.
